UNITED STATES PATENT OFFICE.

BOTHO SCHWERIN, OF FRANKFORT-ON-THE-MAIN, GERMANY, ASSIGNOR TO ELEKTRO-OSMOSE AKTIENGESELLSCHAFT (GRAF SCHWERIN GESELLSCHAFT), OF FRANKFORT-ON-THE-MAIN, GERMANY, A CORPORATION.

PROCESS OF IMPREGNATING ARTIFICIAL AND NATURAL MATERIALS.

1,238,202.

Specification of Letters Patent.

Patented Aug. 28, 1917.

No Drawing.

Application filed August 23, 1916. Serial No. 116,490.

To all whom it may concern:

Be it known that I, BOTHO SCHWERIN, a subject of the German Emperor, residing at Frankfort-on-the-Main, Germany, Wilhelmstr. 34, have invented certain new and useful Improvements in Processes of Impregnating Artificial and Natural Materials, of which the following is a specification.

Attempts have been made to harden natural or artificial stones, cements, or the like by means of compounds of silicic acid such as sodium or potassium silicate (waterglass).

As the artificial stone, cement, etc. contains lime or similar basic binders the effect of treating it with sodium silicate is to produce insoluble calcium silicate and to liberate caustic soda. A portion of the liberated caustic soda may dissolve some of the silicic acid or by the action of the air be changed into sodium carbonate. In both cases, the soluble substances produced have the disadvantage that they effloresce and in doing so may destroy the stone.

By the present invention these faults can be avoided by saturating the stone or the like with soluble or dissolved silicic acid.

Especially advantageous for this purpose is the silicic acid obtained electro-osmotically as described in U. S. Letters Patent 1,182,394, this silicic acid being completely free from electrolytes.

This invention may also be applied for impregnating other materials, such as wood, straw, fibrous material of all kinds, textile goods, bandage material. For fibrous material, textile goods or the like the process also provides a finish or dressing which is particularly suitable for absorbing basic dyestuffs. In many cases it is desirable to render fibrous material capable of resisting heat. This property is furnished by the silicic acid in surprising degree.

Having thus described the nature of the said invention and the best means I know of carrying the same into practical effect, I claim:

1. The herein described process of treating artificial or natural materials, comprising saturating the material with soluble or dissolved silicic acid.

2. The herein described process of treating artificial or natural materials, comprising saturating the material with soluble or dissolved silicic acid free from electrolytes.

In testimony whereof I affix my signature in presence of two witnesses.

BOTHO SCHWERIN.

Witnesses:

HENRY HASPER,
ALLEN F. JENNINGS.
